SAMUEL SEGAL, OF NEW YORK, N. Y., ASSIGNOR TO SEGAL METAL PRODUCTS COMPANY, INC., OF NEW YORK, N. Y., A CORPORATION OF DELAWARE.

MORTISE LOCK.

1,425,060.

Specification of Letters Patent. Patented Aug. 8, 1922.

Application filed February 12, 1920. Serial No. 358,221.

To all whom it may concern:

Be it known that I, SAMUEL SEGAL, a citizen of the United States, and a resident of New York, in the county of New York and State of New York, have invented certain new and useful Improvements in Mortise Locks, of which the following is a specification.

My invention relates to locks for doors or the like and more particularly to locks wherein the locking bolts operate or are actuated vertically and interlock with a keeper fastened to the door frame.

The principal object of my invention is the production of a lock preferably for a swinging door and of the general type indicated above wherein the locking mechanism or casing for holding the locking mechanism is mortised in the door.

A further object of the invention is the production of a novel form of keeper having yielding or compressible ears normally extending in the space between the door and door frame and which shall be adapted to be compressed or forced inwardly by the door upon the closing thereof and to automatically extend outwardly into locking position when the door is completely closed.

Heretofore, particularly in the case of swinging doors having a lock with a vertically operating bolt, it has usually been necessary to fasten the lock casing to the inner face of the door with the end thereof extending beyond the edge of the door so as to permit the locking bolt within the casing to interlock with the keeper on the door frame. The mortising of the lock casing in locks of this character has therefore in cases of this character been impossible as, obviously, the casing would strike against the door frame upon the closing of the door and would prevent its closing. By means of my invention this difficulty has been obviated and I have produced, from a standpoint of strength and appearance, a lock of the above general type which is superior to any locks of which I have knowledge.

In the accompanying drawings showing a practical embodiment of the invention:

Fig. 1 is a front elevation (partly in section) of my improved lock shown mounted in a door.

Fig. 2 is a horizontal section on the line 2—2 of Fig. 1.

Fig. 3 is a vertical cross-section on the line 3—3 of Fig. 1.

Fig. 4 is a horizontal section on the line 4—4 of Fig. 1.

Fig. 5 is a vertical cross-section on the line 5—5 of Fig. 1.

Fig. 6 is a view similar to Fig. 2 but showing a portion only of the parts shown in that figure and in position when the door is partially closed.

Referring more particularly to the several figures of the drawing:

1 indicates a door preferably of the swinging type and 2 the door frame. 3 indicates the outer wall, 4 a removable cover plate constituting the inner wall and 5 an end wall of a casing which contains the locking mechanism, said end wall being also provided with an extension forming a striker plate 6. The casing is provided with lugs 7 on the sides thereof and posts 8 and 9 fastened to the outer wall 3 on which lugs and posts the cover plate 4 is adapted to rest and be detachably secured to the posts by suitable screws. 10 indicates slots in the end wall 5 of the casing which preferably have imperforate, inclined sides as illustrated, said sides forming a portion of the front and rear walls of the casing proper and which are adapted to receive the ears of a keeper as will presently be described. The casing is mortised in the door 1 intermediate the front and rear faces of the door and with the end wall 5 flush with the side of the door and it is held in this position by suitable screws 11 passing through the end wall and into the door. When in proper mortised position, the front and rear walls and other parts of the casing, with the exception of the end wall which is exposed to view, are entirely surrounded and enclosed by the material of the door and are hidden from view.

The locking bolt proper comprises a plate 12 having vertical locking fingers or hooks 13 preferably integral therewith, said plate being also provided with opposed lugs 14 and 14' spaced apart and having inclined opposed surfaces as illustrated. Said locking bolt is adapted to travel or be operated vertically within the casing on tracks 15, 16 and 17 which are preferably integral with the walls of the casing and which act as guides for the locking bolt.

Pivoted to the plate 12 at 18 is the pawl or catch 19. Said pawl is provided with a finger 20 normally extending laterally between the spaced lugs 14, 14'. Said pawl 5 is also provided at its lower end with shoulders 21 and 22. When the bolt is in unlocked position the shoulder 22 engages the top of the post 8 and when in locked position, as shown in Fig. 1, the shoulder 21 10 engages the bottom of post 8 and the lower lug 14' bears against the top of the post which acts as a stop to limit the downward movement of the plate 12. 23 indicates a leaf spring one end of which is fastened to 15 the upper end of the pawl 19 and the other end of which engages a bottom or lug 24 on the plate 12. The action of said spring tends to retain the finger 20 in normal position intermediate the lugs 14, 14' and the 20 lower end of the pawl in engagement with the post 8.

25 indicates a knob operable from the inside of the door having a shank 25' passing therethrough, to the end of which shank, 25 within the casing, is attached the annular plate 26 having opposed operating arms 27 to which studs 28 are fastened. 29 is a spring engaging the studs 28 and the ends of said spring are held in clips 30. Said spring 30 acts to normally retain the arms 27 in vertical disposition or the position shown in Fig. 1.

31 indicates a conventional tumbler-barrel of a cylinder lock which is embedded in the 35 door and is accessible from the outside thereof. Said tumbler-barrel is provided with a screw-threaded inner end 32 having a slot 33, said screw-threaded end extending through and being screwed in the cover 40 plate 4 of the casing. To lock the tumbler-barrel in order to prevent unscrewing of the same from without the door, I have provided an elongated pin 34 extending through the end wall 5 of the casing and through the 45 door, the end of which is screw-threaded as shown (Fig. 2). Said pin is screwed into the door from the end wall 5 to force the end thereof into engagement with the slot 33 thereby preventing rotation of the tumbler-barrel. The spindle of the tumbler-barrel (not shown) which may be turned or operated from without the door by a key inserted in the tumbler-barrel, carries on the 50 end thereof within the casing an operating 55 arm 35.

Mounted in the casing beneath the locking bolt is a spring latch the body of which is indicated at 36. Said body is provided with a head 37 having an inclined side as 60 shown in Fig. 4, which head normally extends through a suitable opening or slot 38 in the end wall 5. Secured to the head 37 are the inwardly and longitudinally extending rods 39 provided at their inner ends with 65 transverse flanges 40 which are adapted to

engage posts 41 mounted in the casing to limit the forward or projected movement of the head 37 through the opening or slot 38. An inward or retracted movement of the head 37 is limited by the engagement of the 70 body 36 with the post 9. 42 indicates springs encircling the rods 39, the forward ends of which engage the head 37 and the rear ends of which engage a transverse plate 43 through which the rods 39 extend, said 75 transverse plate engaging the side of the post 9 as well as suitable shoulders with which the posts 41 are provided and as illustrated in Fig. 1. As is obvious, the action of said spring tends to project the head 37 of 80 the spring latch through the slot 38 and to retain the head in projected or forward position.

44 indicates a latch knob mounted on the inside of the door and having a shank 45 extending therethrough and through the wall 3 of the casing, the inner screw-threaded end of which engages the rotatable hub 46 which extends transversely through the casing. A handle or knob 47 is mounted on the outside 90 of the door and has a shank 48 connecting therewith and extending through the door and through the cover plate 4. Said shank is provided with a screw-threaded end which also engages the rotatable hub 46. Fastened 95 to the hub 46 is a plate 49 having hooked ends or fingers 50 adapted to engage the transverse flanges 40 whereby the latch bolt may be drawn manually into retracted position against the action of the springs 42 100 by turning either the latch knob 44 or the knob 47 in an obvious manner.

51 indicates the front wall or face of a keeper casing and 52 the rear removable cover or wall thereof which carries housings 105 53 preferably integral therewith. Said casing is mortised in the door frame with the front wall or face thereof flush with the side of the frame and is held in position by suitable screws 54. The said front wall or face 110 51 is provided with slots 55 in alignment with the slots 10 in the end wall 5 of the lock casing, with a slot 56 in alignment with the slot 38 in said end wall and with a striker plate 57 preferably integral with the front 115 wall 51. 58 indicates an opening in the door frame registering with the slot 56.

My improved keeper ears comprise perforated members 59 having cam sides or inwardly tapering sides terminating in round-ed ends 59' as illustrated and normally extending in operative position through the slots 55 in the front wall or face 51 of the keeper casing. Said members are provided at either side thereof within the keeper casing with vertical flanges 60 having outer curved surfaces as shown, which flanges span the slots 55 and prevent the members 59 from being withdrawn outwardly there-through. Said vertical flanges 60 normally 130

lie between the side walls of the keeper casing and lugs or projections 61 which are preferably integral with the front wall 51 of the keeper. (See Fig. 5.) 62 indicates rods 5 which are pivoted as at 63 to the rear portion of the members 59 within the casing and which extend within the housings 53. Encircling the inner ends of the housings 53 and bearing against the rear wall 52 of the 10 keeper casing and against the rear portions of the members 59 are the springs 64 whose action, as is obvious, tends to retain the members in projected position, through the slots 55. Said members may be forced or 15 are compressible inwardly into operative position against the action of the springs 64, their inward or retracted movement being limited by the inner ends of the housings 53 which act as stops. When the ears are in 20 retracted position the edges of the extreme rounded outer ends 59' are substantially flush with the outer surface of the front wall 51 of the casing. Also, as is manifest, due to the pivoting of the rods 62 to the 25 members 59, it is immaterial, in order to force or compress the members inwardly within the keeper casing, whether force or pressure is applied to any point of the tapering sides of the members or to the extreme rounded ends 59' thereof. When pressure is applied to one of the tapering sides, for instance, the vertical flanges 60 adjacent that side will rock around the adjacent lugs or projections 61 which act as fulcrums and 30 the outer curved surfaces of these vertical flanges 60 will roll on the side wall of the keeper casing, (see Fig. 6) after which the members are pressed inwardly bodily.

The locking bolt may be operated manually to move the vertical fingers or hooks 13 thereof into locking engagement with the perforated ears 59 of the keeper, as shown in Fig. 1, or to withdraw the same from locking engagement with said ears by turning the knob 25 on the inside of the door or by means of a key inserted in the tumbler-barrel from without the door.

When the locking bolt is in locked position or that position shown in Fig. 1, a 50 turning of the knob 25 causes the lower operating arm 27 to swing upwardly past the inclined face of the lower lug 14'. It then engages and presses against the finger 20, thereby forcing the pawl 19 outwardly on 55 its pivot 18 and against the action of the spring 23 and releasing the shoulder 21 from its engagement with the post 8. A further movement of the lower operating arm 27 by means of the knob 25 forces the 60 same to engage the upper lug 14 and manually raises the locking bolt into unlocked position where it is so held by automatic engagement of the shoulder 22 with the top of post 8 due to the action of spring 23. Obviously, the same result may be accomplished

from without the door by the insertion of a key in the tumbler-barrel 31, the turning of which key will actuate the operating arm 35 and cause the arm to perform the same operation just described as the operating 70 arm 27.

The locking bolt may also be thrown manually from unlocked position into locked position by means of the upper operating arm 27 operated by the knob 25 75 or by means of the operating arm 35 operated by a key inserted in the tumbler-barrel 31. In this case the turning of the knob or key forces the upper operating arm 27 or operating arm 35, as the case may be, to 80 engage and press inwardly the finger 20 thereby releasing the shoulder 22 from engagement with the post 8 and forcing the bolt downwardly by pressure against the lug 14' and allowing the shoulder 21 to engage the post 8 due to the action of spring 23.

As previously described, the perforated ears of the keeper are normally in projected or operative position due to the action of 90 springs 64. Assuming the locking bolt is in retracted or unlocked position and the door is open, a closing of the same if the door is a swinging door, causes the perforated ears to strike against the striker 95 plate 6 which effects a compressing of the perforated ears within the keeper casing and into inoperative position against the action of the springs 64. When the door is completely closed the perforated ears of the 100 keeper are automatically projected by the action of the springs 64 through the slots 10 and into the lock casing, after which the locking bolt may be thrown into locked position in the manner previously described 105 to cause the fingers or hooks 13 to extend through the perforations of the ears of the keeper and interlock therewith. Upon the closing of the door the inclined side of the head 37 of the latch bolt also engages the 110 striker plate 57 of the front wall 51 of the keeper casing, thereby forcing the latch bolt inwardly against the action of the springs 42. When the door is completely closed the head 37 of the latch bolt is 115 automatically projected by the springs 42 through the slot 56 in the front wall 51 and into the opening 58 in the door casing. When the door is closed and the locking bolt is in locked position, the door may not be opened until the locking bolt has been manually withdrawn from locked position in the manner previously described and until the latch bolt has been retracted by means of the latch knob 44 or knob 47. A 120 slight pressure against the door from the inside thereof or a pulling from the outside thereof will then compress the keeper ears within the keeper casing and permit the door to be opened.

What I claim as my invention is:—

1. In a lock, a door adapted to swing around a vertical axis, a keeper fastened to the door frame, an ear on said keeper extending laterally towards the door and into the space between the door and door frame, a casing provided with an end wall flush with the edge of the door and with front and rear walls connected to said end wall, 10 said casing being mortised in the door intermediate the front and rear faces thereof whereby the material of the door entirely surrounds and encloses said front and rear walls of said casing and whereby said end wall only is exposed to view and a vertically operating locking bolt mounted in said casing adapted to interlock with the ear of said keeper.
2. In a lock, a door adapted to swing 20 around a vertical axis, a keeper fastened to the door frame, a casing mounted on said door and provided with an end wall flush with the edge of the door and having a slot therein adapted to receive said keeper and being also provided with front and rear walls connected to said end wall, said front and rear walls being imperforate adjacent said end wall, and a vertically operating locking bolt mounted in said casing and 30 adapted to interlock with said keeper.
3. In lock, a door adapted to swing around a vertical axis, a keeper fastened to the door frame, an ear on said keeper extending into the space between the door 35 and door frame, a casing provided with front and rear walls and an end wall connected to said front and rear walls and having a slot therein adapted to receive said keeper ear, said casing being mortised in 40 the door intermediate the front and rear faces thereof whereby the end wall only is exposed to view, and a vertically operating locking bolt mounted in said casing adapted to interlock with the ear of said keeper.
4. In a lock for a door, a movable keeper fastened to the door frame and adapted to be moved into inoperative position by the door and to assume an operative position when the door is closed and a locking bolt 50 mounted on said door adapted to extend through said keeper to effect an interlocking of said ear and locking bolt.
5. In a lock for a door, a movable keeper fastened to the door frame, a casing mounted 55 on said door and a locking bolt in said casing adapted to interlock with said keeper, said keeper being adapted to be moved into inoperative position by the door and to assume an operative position within said casing when the door is closed.
6. In a lock for a door, a keeper fastened to the door frame, a movable ear on 60 said keeper adapted to be pressed inwardly and a locking bolt mounted on said door adapted to extend through the ear to ef-
- fect an interlocking of said ear and locking bolt.
7. In a lock for a swinging door, a keeper fastened to the door frame, a movable ear on said keeper normally extending laterally 70 towards the door and adapted to be pressed inwardly by the door upon the closing thereof and a locking bolt mounted on said door adapted to extend through the ear to effect an interlocking of said ear and locking bolt. 75
8. In a lock for a swinging door, a keeper fastened to the door frame, a movable ear on said keeper, a casing mounted on said door and a locking bolt in said casing adapted to interlock with the ear of said keeper, 80 said ear being adapted to be pressed inwardly by the door and to be projected into said casing when the door is closed.
9. In a lock for a door, a keeper fastened to the door frame, a movable ear on 85 said keeper, a casing mounted on said door and a vertically operating locking bolt in said casing adapted to interlock with the ear of said keeper, said ear being adapted to be pressed inwardly by the door upon the 90 closing thereof and to be automatically projected into said casing when the door is completely closed.
10. In a lock for a swinging door, a keeper fastened to the door frame, a spring-projected ear on said keeper, a casing mounted 95 on said door and a locking bolt in said casing adapted to interlock with the ear of said keeper, said ear normally extending in the space between the door and the door frame 100 and being adapted to be pressed inwardly by the door upon the closing thereof and to be automatically projected into said casing when the door is completely closed.
11. In a lock for a swinging door, a keeper fastened to the door frame, a spring-projected 105 perforated ear on said keeper, a casing mortised in said door intermediate the front and rear faces thereof, a vertically operating locking bolt mounted in said casing, 110 and a hook on said locking bolt adapted to interlock with said perforated ear, said ear normally extending between the door and the door frame and being adapted to be pressed inwardly by the door upon the closing thereof and to be automatically projected 115 into said casing when the door is completely closed.
12. In a lock for a swinging door, a keeper mortised in the door frame, a spring-projected 120 perforated ear on said keeper, a casing mortised in said door intermediate the front and rear faces thereof and having a slot therein, a vertically operating locking bolt mounted in said casing and operable 125 from within or without the door and a hook on said locking bolt adapted to interlock with the perforated ear of said keeper, said ear normally extending between the door and door frame and being adapted to be 130

pressed inwardly by the door upon the closing thereof and to be automatically projected through the slot in said casing when the door is completely closed.

5 13. In a lock for a door, a keeper ear fastened to the door frame, a rod pivoted to said ear, means for projecting said ear outwardly towards the door and a locking bolt mounted on said door and adapted to extend 10 through said keeper ear to effect an interlocking of said ear and locking bolt.

14. In a lock for a door, a projectible keeper ear fastened to the door frame, a rod pivoted to said ear, a housing within which 15 said rod extends, a spring acting to project said ear into the space between the door and door frame and a locking bolt mounted on said door and adapted to extend through said keeper ear to effect an interlocking of 20 said ear and locking bolt.

15. In a lock for a door, a keeper casing mortised in the door frame and provided with a slot in the front wall thereof, a perforated keeper ear normally projecting 25 through the slot and in the space between the door and door frame, a rod pivoted to said ear, a housing within which said rod extends, a spring acting to hold said ear in projected position, means to limit the movement 30 of the ear through said slot and a locking bolt mounted on said door and adapted to interlock with said keeper ear when the door is closed.

16. In a lock for a door, a keeper casing 35 mortised in the door frame and provided with a slot in the front wall thereof, a perforated compressible keeper ear normally projecting laterally through the slot and in the space between the door and door frame, 40 a rod pivoted to the ear within the keeper casing, a housing within which the rod extends, a spring encircling said housing and bearing against a wall of the keeper casing and said ear and acting to hold said ear in 45 projected position through said slot, means carried by said ear to limit the movement

thereof through said slot and a locking bolt mounted on said door and adapted to interlock with said keeper ear when the door is closed. 50

17. In a lock for a door, a keeper fastened to the door frame, a compressible ear on said keeper normally extending in the space between the door and door frame, a lock casing fastened to the door, a vertically operating locking bolt mounted in said lock casing adapted to interlock with the ear of said keeper, means for operating said locking bolt from within or without the door, a 60 spring-actuated latch-bolt adapted to be automatically projected in the door frame upon the closing of the door and means for operating said latch-bolt from within or without the door.

18. In a lock for a door, a keeper casing 65 mortised in the door frame and provided with a slot, a spring-projected keeper ear mounted in said keeper casing and normally extending through the slot thereof, 70 a lock casing mortised in the door intermediate the front and rear faces thereof, a vertically operating locking bolt mounted in said lock casing and adapted to interlock with said keeper ear, means for operating said locking bolt from within or without the 75 door, a spring-actuated latch-bolt adapted to be projected into the door frame upon the closing of the door, said keeper ear being adapted to be pressed inwardly by the door upon the closing thereof and to be automatically projected through the slot in the lock casing when the door is completely closed and means for operating said latch-bolt from within or without the door. 80

Signed at New York, in the county of 85 New York and State of New York, this 11th day of February, A. D. 1920.

SAMUEL SEGAL.
